UNITED STATES PATENT OFFICE.

ALYCE A. MACDONALD, OF OAKLAND, CALIFORNIA.

MARCELING IRON.

Application filed March 8, 1924. Serial No. 697,866.

To all whom it may concern:

Be it known that I, ALYCE A. MACDONALD, a citizen of the United States, residing at Oakland, in the county of Alameda and State of California, have invented certain new and useful Improvements in Marceling Irons, of which the following is a specification:

The present invention relates to a hair waving device of a type and design particularly for use in forming a so-called flat Marcel wave.

The invention consists primarily in a hair engaging member adapted to be heated and preferably of the well known curling iron type, and which has associated therewith one or more toothed plates or combs adapted for positioning at one side thereof to engage the hair while the hair is held by the iron, and of movement linearly relative to the iron, the plates or combs being designed to be lifted from the hair while the hair remains engaged by the iron.

The objects of the invention are to provide a Marcel waver capable of use by an individual, not necessarily an operator, in the waving of her own hair to form therein flat Marcel waves; to construct a waving device wherein the parts co-operating with the iron, while carried by the iron, are adapted for movement to and from the same to enable the iron to be heated without heating the combs or co-operating parts; to provide a hair waving device including a pair of combs or toothed plates movable in unison in the same direction to enable the operator to wave that portion of the hair immediately adjacent each side of the iron while the iron engages the hair.

This invention is designed to enable the user to form in her hair a series of flat waves representing as nearly as possible hair which is naturally wavy, and to provide a device which a novice can easily master with but little effort.

In order that others may understand my invention, I have illustrated one embodiment thereof in the accompanying drawing in which:

Fig. 1 is a view in side elevation disclosing in dotted lines the combs in extended position.

Fig. 2 is a view in top plan with a portion of one of the guides exposed.

Fig. 3 is a vertical sectional view on line 3—3 Fig. 1 disclosing particularly the cross

sectional formation of the iron, the combs, and the plate connecting the latter.

Fig. 4 is a view in broken perspective illustrating one end of the plate and the manner of its bending around one of the guide fingers.

In the drawings wherein like characters of reference designate corresponding parts, 1 indicates the mandrel and 2 the clamp plate of a hair engaging and waving iron. The mandrel is oval in cross section, and the clamp plate, as illustrated, is curved to embrace a portion of the mandrel. These parts cross and are pivotally connected as 70 at 3, and are provided with parallel handles 4 of the usual type.

In a bracket 5 carried by one of the handles 4 is pivotally mounted to pivot on an axis 6 parallel with the fulcrum point 3, the 75 yoke or bridle 7 of a substantially U-shaped supporting frame. The members 8 of said supporting frame are disposed in parallel relation lying one on either side of the members 1 and 2 as in the drawings. 80 Mounted to slide longitudinally of the members 8 is a suitable plate or uniting member 9, portions of the free edges of which are curled about the members 8 as at 10. The movement of the plate in opposite directions on the members 8 is limited by the inner stop pins 11 and the outer stop pins 12. Secured to each side of the plate 9, one disposed with its back 13 parallel with each rod 8, are the toothed plates or combs 14, 90 the teeth of which are adapted to project downwardly as in the drawings. It will be observed that the movement of the plate 9 longitudinally of the rods 8 will cause a corresponding simultaneous movement of 95 the plates or combs 14.

When in use, the user swings the frame upwardly and by any suitable means heats the members 1 and 2. When the same become heated, that portion of the hair to be 100 waved is engaged between the members 1 and 2, and while tightly held therebetween the combs, which have been moved to the limit of their position in one direction on the members 8, dependent on the direction of the 105 wave to be made in the hair, are lowered into hair engaging position. It will be observed that their proximity to opposite sides of the members 1 and 2 will cause the engagement of the hair projecting immediately 110 beyond the edges of the members 1 and 2. This position is illustrated in Fig. 1. When

in this position, the user grasps the plate 9 and the members 14 and causes a movement of the same lineally of the members 1 and 2 to dotted lined position, Fig. 1. The parts remain in this position for an interval and as soon as the wave is formed, this being readily determined through experience, the frame is swung upwardly in the direction of the arrow, Fig. 1, the engaged portion of the hair is released from between members 1 and 2 and the operation is again performed with a portion of the hair immediately adjacent the waves previously formed.

While the drawings illustrate one of the older types of flame heated curling irons, it is to be understood that if desirable an electric heating element may be incorporated in either member 1 or 2 or in both.

It is to be understood that while I have described and illustrated one embodiment of the invention, I am at liberty to change the form, proportion, size and minor details of construction, so long as I remain within the scope of the appended claims, without in any manner departing from the spirit or sacrificing any of the advantages of the invention.

Having thus described my invention, what I claim as new and desire to protect by Letters Patent of the United States is:—

1. A waving apparatus comprising pivotally connected, co-operating clamp and mandrel members, a frame pivotally connected to one of said members for swinging movement on an axis parallel with the axis of fulcrum of said members, and including a supporting rod lying parallel with one side of said members, and a toothed plate carried by said frame to extend along one side of the iron, said plate mounted for endwise movement on said frame.

2. A waving apparatus comprising pivotally connected, co-operating clamp and mandrel members, a frame pivotally connected to one of said members for swinging movement on an axis parallel with the axis of fulcrum of said members, and including a supporting rod lying parallel with one side of said members, a comb disposed with its face at right angles to the axis of fulcrum of said members and extending along one side of the iron, and means for mounting the comb on said frame for endwise movement longitudinally thereof.

3. A waving apparatus comprising pivotally connected, co-operating clamp and mandrel members, a substantially U-shaped frame pivotally connected to one of said members for swinging movement on an axis parallel with the axis of fulcrum of said members and including a pair of supporting rods lying parallel with the said members one on each side thereof, a pair of toothed plates, one extending along each side of said members, a supporting connection between said plates and frame, whereby the said plates are mounted for movement in unison endwise longitudinally on said frame.

4. A hair waving apparatus comprising a pair of pivotally connected, co-operating clamp and mandrel members, a frame pivotally connected to one of said members for swinging on an axis parallel with the fulcrum of said members, a pair of comb members disposed along respective sides of the members to lie parallel therewith, means for connecting said combs and for mounting the same on said frame to move longitudinally thereof.

In testimony whereof I have signed my name to this specification.

ALYCE A. MACDONALD.
